HOSE COUPLING

George Herbert Moffatt, Ingham County, Mich., assignor to Food Machinery and Chemical Corporation, San Jose, Calif., a corporation of Delaware

Application April 24, 1958, Serial No. 50,597

Term of patent 14 years

(Cl. D91—3)

Fig. 1 of the drawing is a perspective of a hose coupling embodying my design.

Fig. 2 is an end elevational view thereof as seen from the left of Fig. 1, the other end being the same.

The sides of the article not shown are the same in appearance as the side shown.

I claim:

The ornamental design for a hose coupling, as shown and described.
